ATTORNEY.

UNITED STATES PATENT OFFICE.

ABRAHAM KATES, OF PHILADELPHIA, PENNSYLVANIA.

EYEGLASS-FRAME.

1,326,664.

Specification of Letters Patent. Patented Dec. 30, 1919.

Application filed April 18, 1919. Serial No. 291,089.

To all whom it may concern:

Be it known that I, ABRAHAM KATES, a citizen of the United States, residing at Philadelphia, county of Philadelphia, and 5 State of Pennsylvania, have invented a new and useful Improvement in Eyeglass-Frames, of which the following is a full, clear, and exact description, reference being had to the accompanying drawings, which 10 form a part of this specification.

My invention relates to eye glasses, and more particularly to the rims of such glasses, which are commonly made of tortoise shell or imitation shell and are attached on either 15 side of the nose piece or bridge. The great bulk of these rims, although known as "shell", are in reality made of celluloid or similar cheap substitute. On account of its fragility and unreliability, a gold reinforcing ring is commonly embedded in the 20 inner periphery of the shells of spectacle frames to properly support and position the lenses.

In order to insert the lens in such a reinforced rim, it is necessary to split the rim at one point in its periphery so that it may be sprung apart, the lens inserted in the groove, and the ends of the split then fastened together again clamping the lens securely in 25 place. This has been possible in spectacles, the rims being split at the outermost points of their peripheries where the ear pieces or bows are attached, but in eye glasses where 30 there are no such attachments, the rims have not been split and therefore the use of gold reinforcing grooves or "eye-wire" has not been possible.

The object of my invention is to provide eye glass rims with eye-wire reinforcing, by 40 splitting the rims at the innermost points, where they attach to the nose piece, securely attaching the shell and this eye-wire to each other and providing for fastening together the ends of the rim at the split in order to 45 hold the lens properly clamped in position.

In securing the "shell" rim in place, the most serviceable method is to rivet it. The "shell", however, is so fragile that the rivet head in time wears and disintegrates it; but 50 my construction obviates this defect. At each end of the shell I provide an outer metal wall forming a socket for each end, at the split, and run the rivet through so that its outer head coacts with this wall and its inner end is secured to the eye-wire. In this 55 way, while the rivet passes directly through

the shell, it is riveted or soldered into metal at both ends, and the shell is held securely without any chance to work loose.

Having now described the main points of 60 my invention, I will proceed with a description of an embodiment thereof in connection with the accompanying drawings, in which:

Figure 1 is a front view of an eye glass 65 frame.

Fig. 2 is an enlarged front view of the portion of a rim where it joins the bridge.

Fig. 3 is a side view of the portion shown in Fig. 2.

Fig. 4 is an enlarged vertical section through one end of the split rim.

Fig. 5 is a cross-section through same.

Fig. 6 is a perspective view of one end of a split rim with the "shell" shown in 75 imaginary lines.

The eye glass frame consists primarily of a central bridge *a* and on each side a rim composed of an inner metal strip *c* known as eye-wire and a surrounding strip *b* known 80 as "shell". The usual spring clips *d*, Fig. 1, are provided for clamping on the nose, but will not be described as they form no part of my invention.

The composite rim is split, as at *e*, and 85 flanges *f* and *g* are soldered to the ends of the eye-wire, the upper flange *f* extending outward at *h* where it forms one piece with the bridge *a*.

The flanges both have ears *i*, *j* orificed 90 and threaded for the reception of a screw for joining them together. The flanges also both have circular walls *k* and *l*, which form sockets for the ends of the shell *b*. A rivet *m* is passed through each of these walls, the 95 inclosed ends of the shells and the eye-wire, where the end is secured by riveting or soldering.

In assembling, the screw is loosened in ears *i*, *j* and the rim is spread sufficiently to 100 allow a lens to be entered into the groove in the eye-wire. The screw is then tightened up and the flanges clamped together holding the lens properly in position, the rim having been made to fit a standard 105 size lens.

Having now fully described my invention, what I claim and desire to protect by Letters Patent is:

1. An eye glass frame comprising a nose 110 piece and eye-wire rims integral therewith, each rim being split so as to be openable,

means for clamping the split ends together, sockets at both ends of the split, a shell cover for the eye-wire rim terminating in said sockets, and rivets extending radially 5 through the eye-wire, the shell and the socket.

2. An eye glass frame comprising outer and inner peripheral rims, said rims being split, sockets integral with the inner member 10 at both sides of the split and adapted to receive the ends of the outer members therein, rivets through the inner member, the outer member and the sockets, and means for securing the sockets together.

15 3. An eye glass frame comprising a nose piece and grooved eye-wire rims split where they attach to the nose piece, sockets integral with said rims at both sides of the split, split shell rims adapted to encircle the eye-wire 20 rims and terminate in said sockets, rivets through opposite walls of the sockets and the inclosed shell rim, and means to clamp the sockets together.

4. An eye glass frame consisting of a nose 25 piece and split rims, each rim comprising an outer rim of fragile material and a reinforcing inner metal rim, flanges integral with the inner rim at both sides of the split, outer walls on the flanges to form sockets for the

ends of the outer rim, rivets through the 30 inner rim, the outer rim and said walls, and means for clamping the flanges together to close the split rim.

5. An eye glass frame consisting of a nose 35 piece and split rims, each rim comprising an outer rim of fragile material and a reinforcing inner metal rim, flanges integral with the inner rim at both sides of the split, one of said flanges prolonged to be integral with the nose piece, outer walls on the 40 flanges to form sockets for the ends of the outer rim, rivets through the inner rim, the outer rim and said walls, and means for clamping the flanges together to close the 45 split rim.

6. An eye glass frame, comprising a split 50 eye-wire rim, a flange integral therewith at both sides of the split, a split shell rim with its ends abutting on the flanges, outer walls on the flanges forming sockets for the ends of the shell rim and rivets passing radially through the shell and secured at their ends to the eye wire and the outer walls.

In testimony of which invention, I have hereunto set my hand, at Philadelphia, Pa., 55 on this 16th day of April, 1919.

ABRAHAM KATES.
